WRAP DISPENSER

Harper Roisman, 225 N. Bundy Drive,
Los Angeles, Calif. 90049

Filed June 4, 1971, Ser. No. 150,257

Term of patent 14 years

Int. Cl. D7—99

U.S. Cl. D52—2

FIG. 1.

FIG. 2.

FIG. 3.

FIG. 4.

FIG. 5.

FIG. 1 is an upper right front perspective view of a wrap dispenser showing my new design;

FIG. 2 is a right end elevational view thereof;

FIG. 3 is a lower left rear perspective view thereof;

FIG. 4 is an upper right front perspective view of a second embodiment of my new design wherein the front face is rounded from top to bottom rather than flat;

FIG. 5 is an upper right front perspective view of a third embodiment of my new design wherein the front and sides are unitary in form.

I claim:

The ornamental design for a wrap dispenser, as shown and described.
